METER TYPE RELAY HAVING LEVERS FOR
RESETTING ITS CONTACT ARM

Emil B. Marshall, Chicago, Ill., assignor to Western Electric Company, Incorporated, New York, N. Y., a corporation of New York

Application December 16, 1949, Serial No. 133,379

7 Claims. (Cl. 200—110)

1

This invention relates to a meter type relay having levers for resetting its contact arm and more particularly to a control device for preventing the false operation of the contact arm in response to actuation of the resetting levers.

In one kind of meter type relay, a contact arm, oscillatable with the moving coil of the relay, has a magnetic rider which is engageable with either of a pair of magnetized contacts mounted on opposite sides thereof for completing an operating circuit through the contact arm and the magnetized contacts. The magnetized contacts serve to maintain the magnetic rider and contact arm in engagement therewith and a pair of resetting levers operatively connected to a solenoid plunger and controlled by the actuation of the solenoid are provided to restore the contact arm to a neutral zero position intermediate the magnetized contacts. An apparent attraction between the resetting levers and the contact arms operates at times to cause the contact arms to follow one of the resetting levers on the return movement of the resetting levers after they have been actuated to restore the contact arm to zero position and this false movement of the contact arm establishes contact with the magnetized contact and erroneously completes the operating circuit.

It is an object of the present invention to provide a meter type relay having a movable contact arm and resetting levers for restoring the contact arm to a neutral zero position a control device for preventing the false movement of the contact arm in response to the actuation of the resetting levers.

This invention contemplates the addition of a switch device to the above-described meter type relay for short-circuiting the moving coil for a short interval of time during the initial portion of the return movement of the resetting levers to utilize the damping effect of the shorted coil to restrain the contact arm from movement as the resetting levers move away from the contact arm, the shorting switch being in the form of a flexible contact spring mounted on the solenoid plunger for movement therewith and engageable with a pair of binding posts electrically connected to the moving coil.

Other objects and advantages of the invention will be apparent by reference to the following detailed description thereof and the accompanying drawings illustrating a preferred embodiment in which

Fig. 1 is a front elevational or face view of a meter type relay embodying the present invention;

2

Fig. 2 is a cross sectional view of the device shown in Fig. 1 with parts broken away and parts shown in elevation and taken on the line 2—2 of Fig. 1;

5 Fig. 3 is a vertical longitudinal sectional view taken on the line 3—3 of Fig. 1; and

Fig. 4 is a diagrammatic perspective view of a portion of the relay.

The invention as shown herein is applied to 10 a meter type relay similar to the embodiment illustrated in Figs. 4, 5 and 6 of the patent to A. H. Lamb No. 2,062,915, issued December 1, 1936, on a Control Device.

The relay comprises a base 10, on which is 15 mounted a permanent magnet 12 between the poles of which is pivotally supported a coil 14 of a moving system including a needle pointer or contact arm 16, on one end of which is mounted a magnetic rider 18. The rider 18 is 20 movable into engagement with either one of a pair of magnetized contacts 20—20 supported by brackets 22—22 on the base in the path of movement of the rider 18 and on opposite sides thereof to close either of a pair of operating 25 circuits through the contact arm 16 and the contacts 20. When the contact arm 16, in response to a flow of current in the control circuit and the coil, is moved from a normal neutral or zero position midway between the contacts 20 into an operative position with the rider in engagement with one of the magnetized contacts 20, the magnetic attraction between the contacts 20 and the rider 18 serves to retain the contact arm 16 in such operative position.

30 A resetting mechanism is provided for separating the rider 18 from the magnetic contact 20 and restoring the contact arm 16 to a neutral or zero position and comprises a pair of bell crank levers 25—25 pivotally supported in brackets 27 mounted on the base 10 on opposite

35 sides of the contact arm 16 and having buffers 28—28 at their outer ends 30—30 engageable with the contact arm 16. The other ends 31—31 of the bell cranks 25 are directed inwardly toward each other and fit in a groove in a head 40

45 32 formed on a bolt 33, which is secured to the core or armature plunger 34 of a solenoid 35 secured to the base 10. A spring 37 mounted in the closed end of the bore of the solenoid 35 engages one end of the armature plunger 34 and moves it in one direction against a stop 39 50 formed in the base 10.

In response to the energization of solenoid 35, the plunger 34 is retracted, causing the resetting 55 levers 25 to be actuated to move the ends 30—30 thereof and the buffers 28—28 toward each other,

the contact arm 16 being engaged by one of the buffers and moved from its operative position to its neutral position, where it is engaged on opposite sides thereof by both of the buffers 28. Thus, in response to the energization of the solenoid 35, the bell crank levers 25 are oscillated and the ends 30 thereof are moved in opposite directions toward each other to reset the contact arm 16 to its neutral position and, upon the de-energization of the solenoid 35, the spring 37 moves the plunger 34 to its normal position, shown in Fig. 2, which movement effects the return of the bell crank levers to their normal separated or inoperative position, also shown in Fig. 2.

It frequently happens that, because of the attraction between the contact arm 16 and the ends of the bell crank levers 25 or the buffers 28 thereon, after the resetting mechanism has been actuated and the bell crank levers are returning to their normal operative positions, the contact arm 16 will be attracted by one of the bell crank levers and carried therewith to a position where the rider 18 comes within the magnetic influence of the contact 20 and establishes contact therewith. This false actuation of the contact arm 16 and the erroneous closing of the operating circuits through the contact arm 16 and the contacts 20 is highly undesirable and, in order to prevent these false operations in response to the returning movement of the bell crank levers 25, a control device is provided for restraining the coil 14 and the contact arm 16 against movement while the lever ends 30 are being separated therefrom. The control device comprises switch means 43 for short-circuiting the coil 14 for a predetermined short interval of time during the initial portion of the return movement of the resetting levers 25 to utilize the damping effect of the magnetic forces opposing the movement of a closed coil in a magnetic field to restrain the contact arm 16 from movement while the levers 25 are separating therefrom.

Any suitable switch means may be used for shorting the coil 14 during the initial portion of the return movement of the resetting levers 25. In the embodiment illustrated, there is provided a T-shaped member 45 secured at one end to the end of the bolt 33 on the solenoid plunger 34 for movement therewith. The cross arm 46 on the member 45 may engage and bridge a pair of binding posts or terminals 48 in the control circuit to which the coil 14 is electrically connected but preferably the cross arm 46 is adapted to engage contact members 50—50 extending from the binding posts 48 to short-circuit the coil 14. Either the member 45 or the members 50, or both, of the switch means 43 may be flexible to permit a predetermined movement of the plunger 34 after the member 45 has engaged the contact members 50 and shorted the coil 14. The cross arm 46 of the switch member 45 in the normal position of the resetting mechanism is spaced a predetermined distance from contacts 50 and, upon energization of the solenoid and the movement of the plunger 34 in one direction, is adapted to engage the contact member 50 to short the coil 14 as the plunger 34 nears the end of its stroke and as the ends 30 of the levers 25 near the end of their movement, resetting the contact arm to zero position. The cross arm 46 remains in engagement with the contacts 50 and the coil 14 remains shorted as the plunger 34 completes the remainder of its

stroke and the ends 30 of the levers 25 complete the remainder of their resetting movement and the contact member 46 remains in engagement with the contacts 50 during the initial portion 5 of the return stroke of the plunger 34 and during the initial portion of the return movement of the levers 25. Thus the coil 14 is shorted and the contact arm 16 is restrained from movement for a short interval of time during which the ends 30 of the resetting levers 25 are moved away from the contact arm 16 a distance sufficient to eliminate any attractive influence which might occur between the ends 30 of the levers 25 and the contact arm 16. After this initial predetermined interval of return movement has been traversed by the plunger 34, and the ends 30 of the levers are completely separated from the contact arm 16, the cross arm 46 of the switch member 45 is disengaged from the contacts 50 and the coil is thereby restored to its normal or unshorted condition and the levers 25 continue their return movement to their normal inoperative position without exerting any further effect on the contact arm.

It will be apparent, from the foregoing, that the current passing through a control circuit in which the terminals 50 and the coil 14 are connected serves to create a magnetic force which rotates the coil 14 about its axis of rotation and swings the contact arm 16 into its operative position to close the operating circuit through the contact 20, the rider 18 and the contact arm 16. When it is desired to restore the contact arm to its neutral position and to break the operating circuit, the solenoid 35 is caused to be energized, which actuates the resetting mechanism and causes the ends 30 of the resetting bell cranks 25 to move toward each other and return the contact arm 16 to its neutral position. The switch member 45 near the end of the movement of the plunger 34 in one direction, and movement of the lever ends 30 toward each other, short circuits the coil 14 while the lever ends 30 complete their resetting movement, and the member 45 maintains the coil 14 shorted to prevent movement of the contact arm 16 during the initial portion of the return movement of the lever ends 30 to insure the separation of the lever ends 30 from the contact arm 16, after which the coil is unshorted and the resetting arms and the plunger return to their normal inoperative position while the contact arm 16 remains in its neutral position.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. In a meter type relay, the combination of a coil movable in a magnetic field, a contact arm mounted for oscillatable movement with said coil, a magnetized contact mounted in the path of movement of said contact arm and engageable thereby, a resetting lever movable from a normally inoperative position to an operative position and engageable with said contact arm to separate the contact arm from said magnetized contact and restore it to a normal neutral position, means for actuating said resetting lever, switch means electrically connected to said coil, and means operable in timed relation with the movement of said resetting lever for actuating

said switch means to short said coil during a predetermined interval of the movement of said lever.

2. In a meter type relay, the combination of a coil movable in a magnetic field, a pair of terminals to which the ends of said coil are connected, a contact arm mounted for oscillatable movement with said coil, a magnetized contact mounted in the path of movement of said contact arm and engageable thereby, a resetting lever movable to and from a normal inoperative position and an operative position and engageable with said contact arm for disengaging said arm from said magnetized contact and moving it to a normal neutral position, a bridging member, means guiding said bridging member for movement into and out of engagement with said terminals to short said coil, and means for actuating said bridging member in timed relation with the movement of said resetting lever to cause the short-circuiting of the coil during a predetermined interval of movement of said resetting arm.

3. In a meter type relay, a coil movable in a magnetic field, a contact arm mounted for movement with said coil, a magnetized contact mounted in the path of movement of said contact arm and engageable thereby, a resetting lever operable to separate the contact arm from the magnetized contact and move it to a normal neutral position, means including a reciprocal member for actuating said resetting lever, a pair of yieldable terminal members to which the ends of said coil are connected, and a contact member mounted for movement with said reciprocal member and movable thereby into engagement with said yieldable terminals during a predetermined portion of the movement of said reciprocal member to short the coil during a predetermined interval of movement of the resetting lever.

4. In a meter type relay, a coil movable in a magnetic field, a pair of terminals to which the ends of the coil are connected, a contact arm mounted for oscillatable movement with said coil, a magnetized contact mounted in the path of movement of said contact arm and engageable thereby, a resetting lever operable to disengage the contact arm from said magnetized contact and restore it to a normal neutral position, means including a reciprocal member for actuating said resetting lever, and a flexible contact spring mounted on said reciprocal member for movement therewith and operable to bridge said terminals and short circuit said coil during a predetermined portion of the movement of said member.

5. A meter type relay comprising a permanent magnet, a movable coil rotatably mounted in the field of said magnet, a contact arm mounted for movement with said coil, a pair of magnetized contacts mounted in the path of movement of said contact arm on opposite sides thereof, a solenoid having a movable armature, a pair of pivoted resetting levers mounted on opposite sides of said contact arm and operatively connected to said armature for actuation thereby to separate the contact arm from said magnetized contact and restore it to a normal zero position, and switch means electrically connected to said coil and actuatable by the movement of said armature to short-circuit said coil during a predetermined interval of movement thereof.

6. In a meter type relay having a movable coil disposed in a magnetic field, a contact, a contact arm actuated by said coil and movable from a neutral position into engagement with said contact, and magnetic means for yieldably retaining said contact arm in engagement with said contact, the combination therewith of resetting means including a lever for disengaging said contact arm from said contact and moving it to said neutral position, means for actuating said resetting means, switch means electrically connected to said coil for short circuiting said coil, and means operable in timed relation to said actuating means for actuating said switch means to short circuit said coil.

7. In a meter type relay having a movable coil oscillatable in a magnetic field, a contact, a contact arm connected to said coil for movement therewith and movable from a neutral position into engagement with said contact, magnetic means for yieldably retaining said contact arm in engagement with said contact, and a resetting lever movable from a normal position to another position and engageable during said movement with said contact arm to separate the contact arm from said contact and restore it to said neutral position, the combination therewith of switch means electrically connected to said coil for short circuiting said coil, and means for actuating said resetting lever and said switch means in a predetermined timed relation to each other.
